UNITED STATES PATENT OFFICE.

PHILIP T. DODGE, OF NEW YORK, N. Y., ASSIGNOR TO MERGENTHALER LINOTYPE COMPANY, A CORPORATION OF NEW YORK.

TYPOGRAPHICAL MACHINE.

1,158,792.

Specification of Letters Patent.

Patented Nov. 2, 1915.

Application filed September 22, 1914. Serial No. 862,877.

To all whom it may concern:

Be it known that I, PHILIP T. DODGE, a citizen of the United States, residing at New York, in the county of New York and State of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices 15 are released from a magazine or magazines in the order in which their characters are to appear in print and then assembled in line, the composed line transferred to the face of a mold, the mold filled with molten metal 20 to form a slug or linotype against the matrices which produce the type characters thereon, and the matrices thereafter returned by distributing mechanism to the magazine or magazines from which they 25 started.

More particularly, it relates to this kind of machine when equipped with a plurality of movable magazines, any one of which may be brought into operative relation to the assembling and distributing devices, as 30 will subsequently appear more at length from the detailed description.

In the accompanying drawings, I have shown my invention in preferred form and 35 as applied to a linotype machine, but obviously many changes and variations may be made therein, and in its mode of application, which will still be comprised within its spirit. Similarly, it may be adapted to 40 other forms of typographical machines, such as typesetters, type-casters and the like, which handle type or dies, instead of matrices. Generally speaking, I desire it to be understood that I do not limit myself to any 45 specific form or embodiment, except in so far as such limitations are specified in the claims.

Referring to the drawings: Figure 1 is a side view, partly broken away, of a portion 50 of a linotype machine embodying my invention; Fig. 2 is a vertical section through the lower end of the operative magazine, etc.; Fig. 3 is a front view; Fig. 4 is a perpendicular plan view of the magazines, etc.; Fig. 5 is a sectional detail of the raising and

lowering devices; and Fig. 6 is a section on the line 6—6 of Fig. 5.

The matrices X are as usual stored in the superposed inclined magazines A, three of which are shown by way of illustration, 60 and the magazines are arranged so as to be shiftable, both in a horizontal direction and longitudinally, to bring any selected one thereof into operative relation to the assembler raceway B and the single series of escapement devices C at the front of the machine, and the distributing mechanism D and channel entrance E at the rear thereof, the channel entrance being pivotally mounted as at E¹ to permit its removal 70 from operative position when the magazines are changed. The magazines are of the usual form, having their lower ends straight or right angular and standing out of alignment with each other. To facilitate 75 the horizontal shifting of the magazines they are preferably mounted at their forward ends on a pair of carriages F provided with rollers F¹ adapted to travel upon the tracks F², and are sustained at their upper 80 ends by rolls G¹ connected to the frame which supports the magazines and adapted to travel upon the bracket G. The carriages F are connected by the transverse rod F³, which serves also as a handle for 85 moving the magazines forward and backward.

In addition to the horizontal shifting already described, each magazine is capable of a longitudinal movement, so that after it 90 is brought into the proper plane, it may be moved into close relation to the escapements C, and finally removed therefrom when it is desired to bring another magazine into action. To facilitate this relative 95 movement between the superposed magazines, the upper ones are preferably supported upon rollers G³ carried by arms G² connected to the magazines beneath or to their base frames. The means for shifting each magazine individually comprise a rock shaft H, one beneath each magazine, mounted at its opposite ends in the carriages F. Located near its opposite ends are the arms J connected by links K to the 105 magazine or its base frame. The arms J and links K constitute in effect a pair of toggle joints, which when the shaft is rotated are straightened to move the magazine upwardly and finally hold it in elevated or 110

inoperative position. When the shaft is rotated in the opposite direction, the toggle is broken and the magazine descends to the operative position (Fig. 2), wherein it is 5 securely held by the engagement of its base frame A¹ with the rock shaft. In Fig. 1 the upper and lower magazines are shown as elevated, and the intermediate one as lowered.

10 To effect the upward and downward movement of the selected magazine, after it has been brought horizontally into the operative plane, I provide operating means mounted upon the stationary framework and 15 adapted to be engaged with the rock shaft H when in position. These means comprise the single hand lever L mounted upon the short inwardly projecting arbor L¹, and adapted to be moved longitudinally thereon 20 to engage the rock shaft, and then rocked to effect the raising or lowering of the magazine. For this purpose, the end of each rock shaft H is formed with a pair of projecting pins or splines H¹ adapted to be 25 engaged by corresponding recesses in the hub L² of the handle L (Figs. 5 and 6). In order to assist in centering the parts, the end of the arbor L¹ is provided with a spring-pressed pin or plunger L³ adapted to engage 30 a central hole in the end of the shaft H, when the parts are in exact alinement.

After the connection just described has been effected, the handle L is rocked forwardly and the magazine thus brought into 35 operative relation to the assembling devices. When it is desired to bring another magazine into action, the handle is rocked rearwardly and then moved laterally to the position shown by dotted lines in Figs. 3 and 40 5, when the magazines are free to be moved horizontally and another to be brought into the operative plane. Any suitable means may be provided for locking the matrices in the magazines when the latter are out of 45 operative position, such as the well-known cut-away rock shaft M (Fig. 2), provided with the operating finger button M¹ (Fig. 1). As previously stated, I have shown my invention only in preferred form and by way 50 of example, and in a special mode of application, but obviously many modifications and alterations therein, and in its mode of adaptation, will suggest themselves to those skilled in the art, without departure from 55 its scope.

One of the principal features of my invention is the employment of a series of magazines of ordinary construction which can be moved forwardly and backwardly 60 as a whole in the machine and which are so arranged that one or another may be brought into operative position without requiring the tilting of the whole series or the movement of the assembling devices from 65 their operative position in the machine.

Having thus described my invention, its construction and mode of operation, what I claim and desire to secure by Letters Patent of the United States, is as follows:

1. In a typographical machine, the combination of assembling devices, and a plurality of inclined magazines movable as a whole forwardly and backwardly in a horizontal direction and having their lower ends out of alinement with each other, the said magazines being also movable, one independently of another, into and out of operative relation to the assembling devices. 70

2. In a typographical machine, the combination of assembling devices, a plurality of inclined magazines having their lower ends out of alinement with each other, and a supporting frame therefor movable forwardly and backwardly in the machine frame, in a horizontal direction, the said 80 magazines being also movable, one independently of another, relatively to the supporting frame into and out of operative relation to the assembling devices. 85

3. In a typographical machine, the combination of assembling devices, a plurality of inclined magazines arranged thereabove, a supporting frame for the magazines, and horizontal tracks or guides upon which the supporting frame is slidably mounted so as 90 to locate one or another of the magazines directly above the assembling devices, and the selected magazine being movable longitudinally with respect to the supporting frame into and out of operative relation to the assembling devices. 95

4. In a typographical machine, the combination of assembling devices, a plurality of inclined magazines arranged thereabove having their lower ends out of alinement with 100 each other, and a supporting frame for the magazines mounted to slide horizontally in the machine frame, the said magazines being also movable, one independently of another, relatively to the supporting frame into and 105 out of operative relation to the assembling devices.

5. In a typographical machine, the combination of assembling devices, a plurality of inclined magazines arranged thereabove, a supporting frame for the magazines and horizontal tracks or guides mounted in the machine frame and upon which the supporting frame may be slid forwardly and backwardly, the said magazines being also movable relatively to each other to bring the selected one into operative relation to the assembling devices. 115

6. In a typographical machine, the combination of a plurality of magazines, a movable supporting frame therefor, means connected to each magazine for moving it endwise in relation to the supporting frame, and an operating device common to all of said means. 125

7. In a typographical machine, the combination of a plurality of magazines, a movable supporting frame therefor, and movable connections between each magazine and the supporting frame to shift the former endwise in relation to the latter.

8. In a typographical machine, the combination of a plurality of magazines, a movable supporting frame therefor, movable connections between each magazine and the supporting frame to shift the former endwise in relation to the latter, and a single device for operating the shifting connections of one or another of the magazines, as desired.

9. In a typographical machine, the combination of a plurality of magazines, a supporting frame therefor movable to bring any selected magazine into position for use, movable connections between each magazine and the supporting frame to shift the former endwise in relation to the latter, and a single operating device mounted in the machine frame and movable into and out of engagement with the shifting connections of the selected magazine.

10. In a typographical machine, the combination of a magazine, a supporting frame therefor, and connecting members pivoted to each other and to the magazine and supporting frame respectively; whereby the magazine may be shifted endwise in relation to the supporting frame.

11. In a typographical machine, the combination of a single series of escapements,

and a plurality of inclined magazines movable as a whole forwardly and backwardly in a horizontal direction and having their lower ends out of alinement with each other, said magazines being also movable, one independently of another, into and out of operative relation to the escapements.

12. In a typographical machine, the combination of a single series of escapements, a plurality of inclined magazines, a supporting frame therefor and horizontal tracks or guides mounted in the machine frame and upon which the supporting frame may be slid forwardly and backwardly, the said magazines being also movable, one independently of another, relatively to the supporting frame into and out of operative relation to the escapements.

13. In a typographical machine, the combination of a single series of escapements, a plurality of inclined magazines, a supporting frame and horizontal tracks or guides mounted in the machine frame and upon which the supporting frame may be slid forwardly and backwardly, the said magazines being also movable relatively to each other in the supporting frame to bring one or another into operative relative relation to the escapements.

In testimony whereof, I have affixed my signature in presence of two witnesses.

PHILIP T. DODGE.
